VERTICAL SLAT VENETIAN BLIND ANTRATTLE CLIP

Andrew J. Toti, Modesto, Calif.

Application March 15, 1954, Serial No. 416,958

3 Claims. (Cl. 160—177)

2

edges of the shaking slats and whereupon the wider split end 3 will automatically engage over the edge of the next adjacent slat.

The slats of the blind may be of any type, flat, arched, or ribbed, and the slots in the clips made of a size to receive them and function as described.

The clips should be applied to the far side edges of the blinds and will then be quite invisible from the room side. Any number may be applied as may be required, 10 and they may be staggered in height, so as to tie the third slat shown in Fig. 1 to the second one shown in that figure.

When the slats are all folded or tilted to entirely closed position as shown in Fig. 4 the clips may still remain in position if desired. If the clips are applied to the forward edges of the slats they must have their tightly fitting or gripping slots 4 applied to the edge of the slat which swings to carry the open slot 5 away from the run of the blind as indicated in the released position 5' in Fig. 3. Since the slats themselves are highly resilient and the clips are preferably of springy metal, the free slot 5 will automatically disengage its slat when the slats are moved close together.

It is obvious that the clips may be of various forms, 25 and made of various materials including bent out of wire, single or double to the form substantially shown in the drawings, and any similarly functioning "clip" is intended to be covered in my appended claims whether termed a "clip" or by any other name.

I claim:

1. In combination, a Venetian blind provided with vertically arranged turnable slats, an anti-rattle clip extending horizontally across at least two adjacent slats intermediate their length, said clip provided at one end with a slot frictionally gripping a slat to support the clip in horizontal extension, and provided at the opposite end with a slot in position to freely receive another slat as the slats are opened, and swing out of engagement with the latter slat from the frictionally gripped slat as a fulcrum, when the slats are turned toward closed position.

2. In a structure as set out in claim 1 said clip being of spring sheet material bent to provide a frictional slat gripping slot at one end and a wider slot at the opposite end substantially parallel with the gripping slot.

3. In combination, a Venetian blind provided with vertically arranged turnable slats, an anti-rattle clip, comprising a strip of stiff material extending horizontally across at least two adjacent slats intermediate their length, means at one end of said strip arranged to grip opposite sides of one slat adjacent the edge firmly to hold the strip in place in horizontal extension, and means at the opposite end of said strip adapted to freely engage and disengage another slat respectively as the slats are opened and closed.
